(57) **CLAIM**

I claim the ornamental design for a beverage maker, as shown and described.

DESCRIPTION

FIG. 1 is a top, front, right perspective view of a beverage maker, showing my new design;

FIG. 2 is a bottom, front, left perspective view thereof;

FIG. 3 is a front view thereof;

FIG. 4 is a rear view thereof;

FIG. 5 is a right side view thereof, the left side being a mirror image;

FIG. 6 is a top view thereof;

FIG. 7 is a bottom view thereof;

FIG. 8 is another top, front, right perspective view of the beverage maker, shown without an attached bottle;

FIG. 9 is a bottom, front, left perspective view thereof;

FIG. 10 is a front view thereof;

FIG. 11 is a rear view thereof;

FIG. 12 is a right side view thereof;

FIG. 13 is a left side view thereof;

FIG. 14 is a top view thereof; and,

FIG. 15 is a bottom view thereof.

The broken lines are directed to environment and are for illustrative purposes only. The broken lines form no part of the claimed design.

1 Claim, 15 Drawing Sheets
